UNITED STATES PATENT OFFICE.

WILLIAM B. CHURCHER, OF CLEVELAND HEIGHTS, OHIO, ASSIGNOR TO THE WHITE COMPANY, OF CLEVELAND, OHIO, A CORPORATION OF OHIO.

ELECTRICAL SIGNALING SYSTEM AND APPARATUS THEREFOR.

Application filed February 12, 1925. Serial No. 8,673.

My invention relates to electrical signaling systems and apparatus therefor, and particularly to such systems and apparatus as may be usefully employed on automotive vehicles to effect the operation of a signal lamp on the vehicle and for such other purposes as will hereinafter be disclosed.

An object of my invention is to provide an electrical signaling system for an automobile, which will be positive in operation and durable in service.

Another object of my invention is to provide a system of this kind, in which a failure to operate the desired signal will be indicated to the operator at his position remote from the signal, and wherein the signal can not be readily observed.

Another object of my invention is to provide apparatus actuated to give a signal in the event that the aforesaid signal provided as an indicator fails to operate.

Another object of my invention is to provide an improved "stop" light system for automobiles.

My invention will be readily understood by reference to the following description of an embodiment thereof, and in which embodiment reference is had to the accompanying drawings, forming a part of this specification.

Referring to the drawings:

Fig. 1 shows diagrammatically an embodiment of my invention as applied in connection with the stop light of an automobile;

Fig. 2 shows a relay structure employed in the system of Fig. 1, the view being a side elevational view and certain parts hidden from view being indicated by dotted lines;

Fig. 3 shows a top plan view of the relay of Fig. 2;

Fig. 4 shows a front end elevational view thereof; and

Fig. 5 shows a rear end elevational view thereof.

Referring now to the figures of the drawing, in all of which like parts are designated by like reference characters, at 2 I show an electrical signal lamp, which in practice would be installed in a casing at the rear end of the vehicle, in accordance with common

practice for installation of such "stop" lights for automobiles. At 3 I show an electromagnetic relay comprising a core 4, a pair of windings 5 and 6, an armature 7 and a set of contacts comprising the contacts 18 and 19, operable by the movement of the armature 7. At 11 I show an indicator lamp for indicating to the operator, at his driving position in the car and disposed preferably on the dash or instrument board so as to be readily observed by him, when the said lamp is lighted or extinguished. At 12 I show a source of electrical current, such as the storage battery carried by automobiles, and at 13 I show a pair of normally open electrical contacts and which are adapted to be closed by the operator of the automobile in actuating a controlling pedal or lever therefor.

For the practical working of the system of my invention, the relay 3 may be of any well-known form, but for the best carrying out of my invention when applied to automobiles, I prefer to use a relay shown in Figs. 2 to 5, inclusive, which is very compact and at the same time very efficient in operation. This relay comprises a short core 4 carrying an electromagnetic winding composed of two separate coils 5 and 6. The winding in Figs. 2 to 5, inclusive, is designated generally as 14. This winding may be disposed on the core 4 either with its separate coils arranged concentrically or in tandem, but as illustrated in Figs. 2 to 5, inclusive, I have shown them as being concentric. This arrangement permits the winding 6, which is to be of relatively low resistance, to have contained therein more turns of wire for a given resistance than if this coil were disposed in tandem on the core with the coil 5, since the average length of its turns in the latter case would be longer. Carrying the core 4, I have provided a U-shaped return pole 15 having its intermediate portion transverse to the core 4 and its arms parallel thereto extending along either side thereof. Carried near the end of one of the arms, I arrange an end of an armature supporting spring 23 to which is secured by rivets 24, an armature and contact supporting spring, this contact supporting spring being flat and bifurcated towards its contact carrying end

17, so as to separate this contact carrying end into two spring portions, the end of each spring portion carrying a contact, these being shown at 18 and 19 of the drawings.

5 The end of the spring 23 is perforated at 20 to admit a machine screw 21, which passes through it and is screw-threaded, as shown at 22, into the return pole piece arm.

As shown, I preferably form a rearwardly 10 extending loop in the armature supporting spring 23, so as to increase the resiliency thereof at such point and to restrict the flexure of such spring substantially to such spring portion. The armature 7 is secured

15 by rivets 24 to the spring 23 near the loop, but is preferably unattached to such spring at any other portion. This construction permits further independent movement of the armature 7 toward the ends of the mag-

20 netic poles after the contact carrying ends of the spring are stopped by their contacts coming in contact with fixed contacts 25 and 26. These fixed contacts are carried in a block of insulating material 27 secured by a 25 screw 28 to the arm 29 of the return pole piece. The fixed contacts 25 and 26 are thus insulated from the return pole piece 15, which also acts as the frame of the relay and supports all the other parts thereof.

30 Terminals 30 and 31 secured at the bottom ends of the contacts 25 and 26 are provided for the purpose of permitting electrical connections to be made to these contacts, the same being accomplished by the soldering of 35 wires thereto, or otherwise securing wires to these terminals. An L-shaped stop element is also secured to the insulating block 27 by the screw 28, such screw passing through a perforation in the element, as shown at 32,

40 its upper end being bent over the top of the contact carrying end of the spring 17 and is in contact therewith when the relay is in its normal position, as illustrated. The armature 7 is made sufficiently long that 45 its ends overlie the end faces of the return pole piece arms, the magnetic circuit for the armature comprising the core 4, both of the arms of the return pole piece 15 in parallel arrangement, the air gaps between the end

50 faces of the return pole pieces and the armature, the armature itself, and the air gap between the middle part of the armature and the end pole face of the core 4.

I find that a relay constructed as just 55 described is most efficient in operation, since the magnetic circuit is very short and the parts are arranged with a view to most efficient operation. The disposition of the armature and the spring carrying contacts on 60 its end is such that the contacts are made and then rolled on one another, the rolling being accompanied by a sliding contact as the armature continues its movement and the contact carrying bifurcated ends of the 65 spring is deflected by the making of the con-

tacts. This arrangement of armature and spring also permits the relay armature to vibrate quite audibly whenever the relay is actuated under conditions calculated to bring about this condition, and in which actuation one of the contacts carried by the spring controls the circuit, as will be described below.

70 Referring now particularly to Fig. 1, showing the arrangement of the apparatus just described, in a circuit comprising a 75 source of electrical current, a stop light for the vehicle, a controlling switch for actuating the stop light and an indicator lamp for the system, it will be seen that I have arranged circuit conductors interconnecting the various parts, so that I normally place the vehicle stop light 2 in serial circuit with the battery 12, the controlling switch contacts 13 and the high resistance winding 5 of the relay. This arrangement will cause the relay core 4 to magnetically attract the armature 7 whenever the contacts 13 are closed until the relay closes its contacts. The winding 5 may be of any desired resistance, but is preferably higher than that of the winding 6, and I prefer to make this winding sufficiently high in resistance that it will comprise a large number of turns, so as to readily actuate the armature 7 and eliminate the necessity for any delicate adjustment of the relay. This resistance may be so high that the stop light 2 will not be sufficiently energized as to be lighted when included in circuit with the winding. However, I provide a pair of contacts 18-25 closed by the movement of the armature 7 for short circuiting the winding 5 whenever the relay is actuated. This would accomplish the almost immediate demagnetization 100 of the relay and cause the return of the armature to its initial position except for the action of the winding 6, which action will be later described. I will first describe the 105 action of the relay under the assumption that the winding 6 will remain disabled and current cannot pass through it to energize the relay.

110 Upon the short circuiting of the winding 5 by the contacts 18-25, as described, and the subsequent re-opening of these contacts, due to the consequent de-energization of the relay, the winding 5 again receives current and energizes the relay and then again closes the contacts 18-25 to almost immediately 115 de-energize the relay again. This action, involving the rapid closing and opening of the contacts 18-25, will be continuous except, as has been said, for the effect of the winding 6 of the relay. In such a case also the 120 stop light 2 will not be lighted to full brilliancy, but will be lighted to something less than full brilliancy and will "flicker" rapidly or in some cases more slowly, depending upon the adjustment given the moving parts 125 130

of the relay 3 and its contacts. For the purpose of lighting the lamp 2 to full brilliancy, I provide the winding 6, and for indicating the lighting of such lamp to full brilliancy, I provide a lamp 11, the winding and the lamp 11 being placed in serial circuit, together with the contact set 19-26, which are also closed at the same time as the contact set 18-25, or, as I prefer, closed just before the contact set 18-25. I prefer to make the contacts 19-26 just before the making of contacts 18-25, so as to remove the possibility of the vibratory controlling effect of such contacts 18-25, before the contacts 19-26 are closed, in case the latter contacts are closed last. The closing of the contacts 19-26 closes a branch circuit from the storage battery 12, and such branch circuit comprises the contacts 19-26, the winding 6 and the indicator lamp 11, all in serial circuit, and the branch circuit being in branch or multiple with the contacts 18-25 and the stop lamp 2. The main or non-branched part of the circuit comprises the armature 7, the circuit conductor 33, the stop switch contacts 13, the storage battery 12 and the frame of the automobile herein illustrated, as ground in accordance with the common custom in this art. The winding 6 is energized as a result of the closing of the contacts 19-26 and magnetizes, due to such energization, the core 4 and causes magnetic flux to traverse the magnetic circuit, which has been described, and continues the attraction of the armature 7 by the return pole piece arms and the pole face of the core 4 to maintain the relay in actuated position after being preliminarily energized by the energization, due to current through the winding 5. Current through the winding 6 keeps the armature attracted after the contacts 18-25 have closed, short circuiting the winding 5.

However, should the circuit comprising the winding 6 be open-circuited at the time of energization of the relay by current through the winding 5, the vibratory action described will be continued, since then there will be no current through the winding 6 to maintain the relay energized. This vibration of the armature is quite audible. Such a condition may prevail upon a circuit conductor in the circuit of winding 6 being broken, or more commonly will prevail if the indicator lamp is burned out or has in any other way a discontinuous circuit for its filament. It is very desirable, in such a case, that the relay vibrate as described, since then the operator of the vehicle will know that the stop light 2 is improperly lighted and will know also that the indicator lamp cannot be relied upon to give a true indication of the operation of the lamp of the stop light 2.

Having thus described my invention in a

specific embodiment and a specific relay structure for carrying out the invention of my system, I am aware that numerous and extensive departures may be made from the embodiment of my invention herein illustrated and described and the apparatus therefor, but without departing from the spirit of my invention. 70

I claim:—

1. In an electrical signaling system, the combination with an electric signal lamp, a pilot lamp therefor, a source of electrical current, electromagnetic means controlling the flow of current from the source through both of said lamps, said electromagnetic means comprising a pair of electrowindings and a pair of sets of electrical contacts, each contact set comprising a pair of contacts adapted to be closed upon flow of current through either of said windings, a common controlling switch, each of said lamps being included in serial circuit with a different one of said windings, said controlling switch and said source of current, one of said windings being a high resistance winding, one of said contact sets being connected in multiple circuit with said high resistance winding, the other of said contacts being connected in serial circuit with the other winding and means adapted to operate said controlling 95 switch. 85

2. In an electrical signaling system, the combination with an electric signal, a pilot signal therefor, a source of electrical current, electromagnetic means controlling the flow of current from the source through both of said signals, said electromagnetic means comprising a pair of electrowindings and a pair of sets of electrical contacts, each contact set comprising a pair of contacts adapted to be closed upon flow of current through either of said windings, a common controlling switch, each of said signals being included in serial circuit with a different one of said windings, said controlling switch and said source of current, one of said windings being a high resistance winding, one of said contact sets being connected in multiple circuit with said high resistance winding, the other of said contacts being connected in serial circuit with the other winding and means adapted to operate said controlling switch, said high resistance winding being of such a resistance that current from the source directed therethrough to the serially connected signals will be insufficient to operatively energize the signal. 110 100 105 115 120

3. In a signalling system, the combination with a pair of lamps, a pair of magnet windings, an armature adapted to be moved by electrical current directed through one of said windings and to be maintained in one of said positions after an initial movement by current directed through the other winding, a pair of electrical contacts, a plurality 130 125

of sets of contacts adapted to be closed upon movement of the armature responsive to flow of current through said first winding, one of said contact sets being connected in multiple circuit with one of said windings, the other said contact being connected in series with said second winding, a source of current, and a controlling switch adapted to direct current from the source through one

of said lamps and through said first winding and means comprising circuit conductors adapted to direct current from the source through said second set of contacts and said second winding to the other lamp. 10

In testimony whereof I hereunto affix my ¹⁵ signature this 3rd day of February, 1925.

WILLIAM B. CHURCHER.
